UNITED STATES PATENT OFFICE.

SAMUEL MORRIS, OF NEWARK, OHIO, ASSIGNOR OF ONE-HALF TO MOSES H. NEIL, OF COLUMBUS, OHIO.

CAR-COUPLING.

SPECIFICATION forming part of Letters Patent No. 746,729, dated December 15, 1903.

Application filed July 27, 1903. Serial No. 167,152. (No model.)

To all whom it may concern:

Be it known that I, SAMUEL MORRIS, a citizen of the United States, residing at Newark, in the county of Licking and State of Ohio, have invented certain new and useful Improvements in Car-Couplings; and I do hereby declare the following to be a full, clear, and exact description of the invention, such as will enable others skilled in the art to which it applies to make and use the same.

The object of this invention is to provide an improved coupling of simplified construction of the kind adapted to automatically couple the cars.

15 The invention consists in the construction hereinafter described and claimed.

In the accompanying drawings, showing an embodiment of the invention, Figure 1 is a horizontal sectional view of the draw-head, 20 exposing in top plan view the operative parts of one coupler in the coupled position. Fig. 2 is a similar view showing the same parts in uncoupled position. Fig. 3 is a similar view showing the same parts in coupled position on 25 a curved track. Fig. 4 is a vertical sectional view showing in full lines the lock down and in broken lines the lock up. Fig. 5 is a front or end view showing the coupled position of the parts. Fig. 6 is a perspective of the lock. 30 Fig. 7 is a perspective view of a lever or "kicker" for moving the knuckle to open position. Fig. 8 is a perspective of the knuckle.

Like characters of reference designate corresponding parts.

35 The draw-head 1 has an appropriate cavity to receive the inner leg of the knuckle 2, the lock 3, and the kicker 4. The draw-head also has a boxed-in cavity or hood 1^a above the main cavity, into which the lock can be lifted and guided. The knuckle 2 has a leg 2^a, on the outer side of the end of which are formed lock-engaging shoulders 2^b and 2^c, the shoulder 2^c being set back of the shoulder 2^b and having adjacent thereto a seat 2^d, upon which the lock rests when engaging the said shoulder 2^c. The knuckle-leg 2^a also has at its rear side a toe 2^e, adapted to engage a projection 1^b in the head of the cavity, as herein-after described.

50 The lock 3 consists of a rectangularly-shaped block having a vertical rib 3^a project-

ing from its side and at its lower end a stud 3^b projecting horizontally from the rib. The lock slides vertically in an opening in the upper wall of the draw-head, the edges 3^c and 3^d serving to guide and hold the lock from horizontal play. Attached to the upper end of the lock is a rod 3^e, passing up through the hood 1^a, by means of which the lock can be lifted.

55 The kicker or knuckle-opening device 4 consists of a bell-crank lever. This is fulcrumed on a pin 4^a in the upper wall of the draw-head in rear of the knuckle and in such position that the lower end of the depending arm 4^b of the lever may strike the leg of the knuckle and impel it outward to open position. The end of the arm 4^b can be made rounded, so as to properly bear upon the leg. The upper arm 4^c of the kicker reaches forward, so as to lie above and in the path of the stud 3^b on the lock 3.

60 The operation is as follows: Assuming the parts to be in the position indicated in Fig. 1 and it is desired to put the parts into position to couple, the lock is lifted until the stud 3^b strikes and lifts the upper arm of the kicker. This will throw the knuckle outward, as seen in Fig. 2. In this position the lock will rest on the upper face of the end of 65 the leg, and in this position the coupling will be ready to connect with another. When hit with another approaching coupling, the lock will drop by gravity, first on the seat 2^d and then to the floor of the draw-head cavity. If 70 the cars come together on a curved track, the lock will stop on the seat 2^d and the knuckle will be locked and the cars coupled by the engagement of the rib 3^a and projection 3^b with the shoulder 2^c. When the cars run 75 onto a straight track, the knuckles are automatically, by the alinement of the cars, turned into position where the lock will drop, so that the rib 3^a and projection 3^b will engage the shoulder 2^c. When the cars come 80 together, in the first instance, on a straight track, the lock will not stop on the seat 2^d, but pass immediately down to the last-described position. The lock in the construction shown does not operate the kicker until 85 it is lifted high enough to permit the leg of the knuckle to pass under the lower end of 90

95 100

the lock. The lower end of the lock when completely down is braced by a projection 1^c on the bottom of the coupler-cavity.

What I claim, and desire to secure by Letters Patent, is—

1. In a car-coupling, the combination of the knuckle having a leg with a lock-engaging shoulder, a lever having one arm adapted to actuate the leg to throw the knuckle into uncoupled position, a sliding lock having a rib 3^a with a projection 3^b at its lower end, said rib and projection 3^b to engage the locking-shoulders of the knuckle-leg, and the projection 3^b also to actuate the other arm of the aforesaid lever.

2. In a car-coupling, the combination of

the knuckle having a leg with two lock-engaging shoulders, a lever having one arm adapted to actuate the leg to throw the knuckle into uncoupled position, a sliding lock having a rib 3^a with a projection 3^b at its lower end, said rib and projection to engage the locking-shoulders of the knuckle-leg, and the projection 3^b also to engage the other arm of the lever to throw the knuckle to open position.

In testimony whereof I affix my signature in presence of two witnesses.

SAMUEL MORRIS.
